DESIGN FOR A SPORTS JACKET

Henry Nieberg, New York, N. Y.

Application August 23, 1939, Serial No. 86,851

Term of patent 3½ years

To all whom it may concern:

Be it known that I, Henry Nieberg, a citizen of the United States of America, residing in New York city, in the Borough of Manhattan, county and State of New York, have invented a new, original, and ornamental Design for a Sports Jacket, of which the following is a specification, reference being had to the accompanying drawing, forming part thereof, wherein:

I claim:

The ornamental design for a sports jacket, substantially as shown.

HENRY NIEBERG.
